W. A. HAMBIDGE

SWING

Filed July 7, 1925

FIG. 2

Inventor

W. A. Hambidge

By Watson E. Coleman
Attorney

UNITED STATES PATENT OFFICE.

WILLIAM A. HAMBIDGE, OF UPLAND, INDIANA.

SWING.

Application filed July 7, 1925. Serial No. 42,059.

To all whom it may concern:

Be it known that I, WILLIAM A. HAMBIDGE, a citizen of the United States, residing at Upland, in the county of Grant and State of Indiana, have invented certain new and useful Improvements in Swings, of which the following is a specification, reference being had to the accompanying drawings.

This invention relates to swings, and the general object of the invention is to provide a swing of a very simple but improved construction so formed that the person seated in the swing may swing himself without the necessity of anybody pushing him.

15 A further object is to provide a device of this character which is particularly adapted for small children and in which the swinging of the device is effected not only by the hands but by the feet of the swinger.

20 Other objects will appear in the course of the following description.

My invention is illustrated in the accompanying drawing, wherein:—

25 Figure 1 is a perspective view of a swing constructed in accordance with my invention;

Figure 2 is a vertical sectional view through the swing;

30 Figure 3 is a horizontal sectional view taken just above the seat.

Referring to this drawing, 10 designates the seat of the swing which is narrow at its forward end so as to permit the legs of the operator to hang down on each side of the forward prolongation 11 of the seat 10. Pivoted to this forward prolongation of the seat 10 are the two levers 12, the pivot pins being designated 13. These levers at their upper ends are connected by a cross bar 14 and at their lower ends by a cross bar 15. These cross bars are cut away adjacent their ends to form handles for the bar 14 and foot rests for the bar 15.

45 Extending downward from an upper support of any suitable character are a pair of chains, ropes or other flexible connections 16. These extend downward through eyes 17 in the handle bar 14 and are connected to the foot bar 15. These connections 16 extend loosely through the openings 17. Attached

50 to the rear end of the seat 10 is a flexible support 18 which extends upward and is connected to any suitable supporting structure as, for instance, the roof of a piazza, the ceiling of a house, etc. It will be seen that 55 the handle bar 14 is disposed in a downwardly and forwardly inclined plane or may be disposed in a horizontal plane.

With this construction it is obvious that the child seated upon the swing may operate 60 the same by alternately pulling and pushing upon the handle 14. When the handle is pushed inward the feet are pressed against the foot bar 15 and the swing is propelled forward. When it is desired to propel the 65 seat rearward, the handle 14 is pushed outward and the foot bar 15 will move inwardly. Thus the swing may be very readily started and its oscillations increased by operating these bars 14 and 15. At the same time the 70 child is held from falling out of the swing by the fact that the child's legs are astride the portion 11 and rest upon the cross bar 15 and the child is prevented from being projected forward from the swing by the levers 75 12 and the handle 14. As the child is grasping the handle bar 14, it is obvious that he is not likely to tumble rearward, particularly in view of the connection 18.

I claim:—

1. A swing of the character described comprising a seat having a forward prolongation, a lever pivoted to the forward prolongation and extending above and below the seat, a handle cross bar mounted upon the upper 80 end of the lever, a foot cross bar mounted upon the lower end of the lever, a pair of flexible connections extending downward from a suitable support and engaged with the ends of the handle bar and with the ends 85 of the foot bar, and a flexible connection extending downward from the support and engaged with the rear end of the seat.

2. A swing of the character described comprising a seat formed with a relatively narrow, forward prolongation, a lever extending upward on each side of the prolongation and pivoted thereto, a handle bar engaged with the upper ends of the levers and extending 90 transversely thereof and disposed at a slight 95 100

inclination to a horizontal plane, a foot bar attached to the lower ends of the levers and extending transversely thereof, a pair of flexible connections extending downward from a support and passing through perforations in the ends of the handle bar and attached at their lower ends to the extrem- ities of the foot bar, and a flexible connection attached to the rear end of the seat and extending upward to a support. In testimony whereof I hereunto affix my signature,

WILLIAM A. HAMBIDGE.
